ATTORNEY

UNITED STATES PATENT OFFICE.

AUGUST VESTERLING, OF BATTERSEA PARK, LONDON, ENGLAND.

FILING OF RECORDS, LETTERS, AND OTHER DOCUMENTS.

1,142,644.

Specification of Letters Patent.

Patented June 8, 1915.

Application filed March 23, 1914. Serial No. 826,809.

To all whom it may concern:

Be it known that I, AUGUST VESTERLING, a subject of His Majesty the King of England, residing at 107 Castle street, Battersea Park, in the county of London, Kingdom of England, have invented certain new and useful Improvements in or Connected with the Filing of Records, Letters, and other Documents, of which the following is a specification.

This invention relates to improvements in, or connected with the filing of records, letters and other documents.

The object of the invention is to provide loose-leaf books, files and the like having rings, prongs or other like leaf-retaining devices with improved means to prevent the loose leaves or papers filed therein from jamming on said rings, prongs or other leaf-retaining devices and the consequent fouling of the covers of the book, file or the like which would tend to prevent closing of the same, and the leaves or papers from tearing on said rings, prongs or devices at their perforations or slots; and to guide the leaves or papers smoothly along said rings, prongs or the like when the book or the like is being opened and closed.

A convenient manner of carrying out the invention is hereinafter described with reference to the accompanying drawings in which:—

Figure 1 is a cross section on the line 1—1 of Fig. 2. Fig. 2 is a plan on a reduced scale, showing two of the improved devices fitted to a convenient form of loose-leaf book having two outer covers and provided with removable rings fitted into a solid slotted strip on the back of the book. Fig. 3 is a transverse sectional view of a loose leaf book illustrating the manner of hinging the leaf retaining members to the covers. Figs. 4 and 5 are detail perspective views partly in section, of slotted leaf lifting members provided with wires or pins passed through loops on the said members for retaining the same on the leaf retaining rings.

According to the invention a loose-leaf book, file or the like is fitted with one or more hinged devices which are mounted on one, two or more of the leaf-retaining rings, prongs or the like in such manner that when the book, file or the like is closed the device or devices operate to lift and push the leaves

or papers filed on said rings, prongs or the like on and along the same for the purposes above mentioned. These leaf-lifting devices may comprise, as shown in the drawings, two inside covers each formed of an inner strip 12 and an outer flap 13 which are hinged together at 14 and perforated or slotted at 15 to enable them to be mounted on one, two or more of the rings, prongs or the like, which latter may be of any construction and shape and permanently or removably fitted inside the book, file or the like and either to the back or to one cover of the latter as desired. The slots or perforations 15 in the inside covers 12—13 are of a correlative size, number and position with those in the papers. The leaf-retaining devices shown in the drawings are in the form of sectional rings 7 which are removably fitted in a slotted member 16 fixed to or formed integrally with the back 17 of the book, file or the like, but the latter may be of any known or convenient type as desired.

When the outer covers 11 of the book are closed the two outer flaps 13 of the leaf-lifters are caused to ride and rise on the peripheries of the rings 7 and open out away from the back 16 by the leverage of the inner strips 12, as shown by dotted lines in Fig. 2, and consequently push and lift the leaves or papers in the book along and on the rings and prevent wedging of the same inside the book and fouling of the outer covers 11 of the latter which would tend to prevent closing of the book, and cause wearing and tearing of the perforations punched in the leaves or papers. The leaf-lifters 12—13 also enable the book, file or the like to be opened and closed quickly and smoothly, and large and thick books, files and the like to be used.

The leaf-lifters 12—13 may each be formed with a single row of slots 18 and 19 instead of with two rows of perforations as shown in Figs. 1 and 2 of the drawing, and be retained on the leaf-retaining devices by means of pins or wires passed through loops or the like formed on said lifters and through said devices.

In Fig. 4 of the drawing the slotted member 12 is provided with aligned rings or loops 20 through which passes a wire or pin 21, while in Fig. 5 the slotted member 13 is

22
provided with loops 22 located at opposite sides of the slots and receiving short pins 23.

The inner edges of the strips 12 of the leaf-lifters 12-13 may be adapted to rest against ridges or other like raised parts such as shown at 6 in the drawings, or said strips may be directly and permanently or detachably hinged to the book, file or the like by a flexible strip 24. The flexible strip 10 24, which is preferably double to embrace the outer edge of the member 13, as shown, is secured to the same and to the top surface of the back of the book by adhesive material or other means.

15 Instead of the wide covers as shown in the drawings the leaf-lifters may be in the form of narrow strips or levers similarly hinged together and each mounted on, or fitted to, or linked with one or more of the leaf-retaining devices, and be adapted to act in like manner to the covers, and one, two or more of these levers may be used at a time.

The flaps 13 may be of various sizes in relation to the covers 11 when outer covers are used, and the size and form of the complete lifters, particularly the strips 12 thereof, depend upon the thickness of the book, file or the like, the size of the rings, prongs or other leaf-retaining devices therein, and the 25 number of leaves or papers filed or to be filed. Thus the thicker the book, file or the like, the larger the leaf-retaining devices and the greater the lift required, the wider will be the strips 12 and the greater the leverage obtained thereby.

The leaf-lifting covers, strips or levers may be made of millboard fiber, metal or other material or a combination of materials, and be covered with cloth, paper, or 40 other suitable material.

Means are provided whereby the inner and outer members of the leaf-lifters are maintained slightly separated when the book, file or the like is fully open, and 45 whereby the lifters commence to act directly said book, file or the like starts to close. For this purpose the top surface of the back 16 may be sloped as shown in the drawings, or studs or other projections may be fitted on 50 said back. The two members of the leaf lifter may be made so as to tend to spring open by making the covering cloth a little tight, or in other convenient manner. The holes or slots formed in the lifters may be 55 eyeleted with metal or other material.

One or more of the leaf-lifting covers, strips or levers may be mounted on one or both sides of the rings, prongs or other leaf-retaining devices as desired, and according 60 to the construction of the book, file or the like.

What I claim as my invention and desire

to secure by Letters Patent of the United States, is:—

1. In a loose leaf book, file or the like having rings, prongs, or other leaf retaining devices upon which the leaves or papers are filed, one or more leaf lifting devices mounted on two or more of said leaf retaining devices, each leaf lifting device formed of 65 members hinged together and adapted to lift and push the leaves or papers on said leaf retaining devices when the book, file or the like is closed.

2. In a loose leaf book, file or the like having one or more rings, prongs, or other leaf retaining devices upon which the leaves or papers are filed, one or more leaf lifting devices comprising an inner perforated member and an outer perforated member hinged 70 to the inner member, said leaf lifting devices being adapted to be mounted on one or more of said leaf retaining devices and adapted to lift and push the leaves or papers on said leaf retaining devices when the book, file or the like is closed.

3. In a loose leaf book, file or the like having one or more rings, prongs, or other leaf retaining devices upon which the leaves or papers are filed, one or more leaf lifting devices comprising an inner perforated member hingedly connected to the book, file or the like, and an outer perforated member hinged to the inner member, said leaf lifting devices being adapted to be mounted on 90 one or more of said leaf retaining devices and adapted to lift and push the leaves or papers on said leaf retaining devices when the book, file or the like is closed.

4. In a loose leaf book, file or the like having one or more rings, prongs, or other leaf retaining devices upon which the leaves or papers are filed, one or more leaf lifting devices comprising an inner perforated member and an outer perforated member hinged 100 to the inner member, said leaf lifting devices being adapted to be mounted on one or more of said leaf retaining devices and adapted to lift and push the leaves or papers on said leaf retaining devices when the book, file or the like is closed, and one or more wires 105 passed through loops, rings or the like formed on said members and through the said leaf retaining devices to retain the leaf lifting devices on said rings, prongs, or 110 other leaf retaining devices.

In testimony whereof I have signed this specification in the presence of two subscribing witnesses.

AUGUST VESTERLING.
